FOREIGN PATENT DOCUMENTS

CA 1117489 2/1982

Primary Examiner — Cynthia R Underwood(74) *Attorney, Agent, or Firm* — Christine Flanagan(57) **CLAIM**

The ornamental design for a modular offset hook, as shown and described.

DESCRIPTION

FIG. 1 is a perspective view of the modular offset hook of the present invention, with product thereon.

FIG. 2 is a perspective view of the modular offset hook.

FIG. 3 is a left side view of the modular offset hook.

FIG. 4 is a right side view of the modular offset hook.

FIG. 5 is a top down view of the modular offset hook.

FIG. 6 is a bottom up view of the modular offset hook.

FIG. 7 is a front view of the modular offset hook; and,

FIG. 8 is a rear view of the modular offset hook.

The broken lines are for the purpose of illustrating the environment of the design only and form no part of the claimed design.

1 Claim, 4 Drawing Sheets(56)
